UNITED STATES PATENT OFFICE.

SHERARD OSBORN COWPER-COLES, OF LONDON, ENGLAND.

MANUFACTURE OF CARTRIDGE-CASES AND SIMILAR ARTICLES.

No. 895,164.

Specification of Letters Patent.

Patented Aug. 4, 1908.

Application filed May 20, 1907. Serial No. 374,806.

To all whom it may concern:

Be it known that I, SHERARD OSBORN COWPER-COLES, a subject of the King of Great Britain, residing at Grosvenor Mansions, 82 Victoria street, Westminster, London, England, have invented new and useful Improvements in the Manufacture of Cartridge-Cases and Similar Articles; and I do hereby declare that the following is a full, clear, and exact description of the invention, which will enable others skilled in the art to which it appertains to make and use the same.

My invention relates to the electrolytic production of cartridge cases and other hollow articles or tubes, shells or cylinders with an end or ends on a revolving mandrel and has for its object to produce such articles of a uniform quality of copper.

According to the invention I prepare a mandrel of brass or other suitable metal, which is made to correspond to the internal dimensions of the cartridge case or other hollow object it is desired to produce as heretofore but the mandrel is caused to revolve at a high rate of speed, say 1000 to 1500 feet peripheral speed per minute, in an electrolyte containing the metal or metals it is desired to deposit as an alloy, and at the same time the electrolyte is projected under pressure on that portion of the mandrel which does not revolve at the required critical speed. If the cartridge case for example is to be made of brass, brass anodes are used, if of copper, copper anodes. Or, the cartridge cases may be built up of two or more metals; for instance iron or zinc can first of all be deposited on the mandrel and backed with brass and copper. The electrolyte is injected under pressure on to the center of the case end or bottom, to insure the bottom, or what corresponds to the end, of the cartridge case in which the cap is placed, being smooth and of equal quality to the remainder of the case. By this means I am enabled to produce a cartridge case or other article with the bottom as smooth as, and of equal quality to, the remainder of the case, which would otherwise not be possible, as the copper near the axis of the mandrel which has a low peripheral speed would be unsound and useless for commercial purposes. The cartridge case or other article, after removal from the mandrel, may be drawn or spun down at the end to the desired form.

In order that my invention may be more

clearly understood, I have illustrated it in the accompanying drawings in which

Figure 1 is a sectional elevation of an apparatus which may be conveniently used in carrying out my invention. Fig. 2, is a plan view thereof, and Fig. 3 is a sectional view of a detail hereinafter described and drawn to a larger scale.

Similar reference letters indicate identical parts throughout.

a is the electrolytic tank and *b*, *b* are the cathodes which are of a shape and size corresponding to the interior of the article to be made, in the arrangement illustrated, a cartridge case. Each of these cathodes *b* is secured to a screw-threaded pin *c* (see Fig. 3) upon the lower end of a spindle *f*, the upper end of which passes through a plate *d* and has keyed upon its projecting end a toothed pinion *e*. The plate *d* is circular in shape and the cathodes *b* are arranged around its periphery, as clearly shown in Fig. 2, and the said plate is mounted upon a central upright spindle *f* held in bearings *f*¹ and *f*² and adapted to be driven by means of the pulley *g*. The upright spindle *f* has also mounted upon it a sleeve *h* which carries at its upper end a pulley *h*¹ by means of which it may be rotated at a slower speed than the spindle *f*, and at its lower end a toothed wheel *i* above the plate *d* and gearing with an intermediate wheel *j* rotatably mounted upon the upper side of the said plate *d* and adapted to engage with each of the pinions *e* so that each of the said pinions *e*, and consequently, the cathode *b* in connection therewith, is turned upon its axis in addition to the motion which it shares with the plate *d* around the axis of the spindle *f*.

The anode is formed of the ring *k* which is L-shaped in cross-section, as clearly shown in Fig. 1, the lower limb of the L serving to deposit metal upon the base of the cathode and the upright limb to deposit metal upon the broader portion of the side of the said cathode *b*. The metal for deposition upon the neck or upper portion of the cathode to be subsequently drawn to form the neck of the cartridge is supplied by means of the upper portion of the anode which comprises a series of sections *l*, *l* which together form a ring inclosing the upper parts of the circular series of cathodes *b*. These sections *l* can be adjusted in position so as to obtain a different current density at this part than obtains at the lower part *k* of the anode and this is

effected in the arrangement illustrated by means of the wedges *m* which are suspended by rods *m'* from the brackets *n*, *n* secured to the inside of the tank *a* and which coöperate with wedges *o* suspended from the lower ends of rods *p*, the upper ends of which extend through holes in the aforesaid brackets *n* and have their projecting ends screw-threaded to receive nuts by turning which the said 10 wedges *o* can be raised and thus in conjunction with the wedges *m* force the sections *l* nearer to the cathodes *b* and thereby adjust the relative current densities at the two portions of the anodes. The lower limb of the 15 part *k* of the anode is provided with holes *k'*, *k'*, to permit of the passage of the electrolyte.

Current is supplied to the cathodes *b* through the medium of the brush *q* and to 20 the anode sections *l* through the medium of the suspension rods *m'*. *r* is a spraying pipe for causing the electrolyte to be projected through the holes *k'* on to the cathodes.

Having now fully described and ascertained my said invention and the manner 25 in which it is to be performed, I declare that what I claim is:—

1. The herein described process for producing cylindrical articles closed at one end, 30 which consists in immersing a mandrel in an electrolyte, electrolytically depositing a suitable metal upon the exterior of lateral portions and one end of the mandrel, rotating the mandrel at high speed in the electrolyte 35 during the electro deposition, and simultaneously projecting portions of the electrolyte against the end face of the mandrel, removing the deposited metal in integral form from the mandrel and drawing portions of 40 the metallic articles so formed to reduce diameter, to give the desired shape, substantially as described.

2. The herein described process for producing cylindrical articles closed at one end, which consists in immersing a mandrel in an electrolyte, electrolytically depositing a suitable metal upon the exterior of lateral portions and one end of the mandrel, rotating the mandrel at high speed in the electrolyte during the electro deposition and simultaneously projecting portions of the electrolyte against the end face of the mandrel, removing the deposited metal in integral form from the mandrel, and shaping the hollow metallic article so formed, substantially as described.

3. The herein described process for producing cylindrical articles closed at one end, which consists in immersing a mandrel in an electrolyte, electrolytically depositing a suitable metal upon the exterior of lateral portions and one end of the mandrel, rotating the mandrel at high speed in the electrolyte during the electro deposition and simultaneously projecting portions of the electrolyte against the end face of the mandrel, and removing the deposited metal, in integral form from the mandrel, substantially as described.

4. The herein described process for producing cylindrical articles closed at one end, which consists in immersing a mandrel in an electrolyte, electrolytically depositing a suitable metal upon the exterior of lateral portions and one end of the mandrel and rotating the mandrel at high speed during the electro deposition, and removing the deposited metal in integral form from the mandrel, substantially as described.

SHERARD OSBORN COWPER-COLES.
